LOCK SLIDER

Emmett C. Hartley, Meadville, Pa., assignor to
Talon, Inc., a corporation of Pennsylvania

Application February 25, 1942, Serial No. 432,296

7 Claims. (Cl. 24—205.5)

This invention relates to slide fasteners and, in particular, to the provision of new and improved sliders therefor.

It is the object of this invention to provide a slider embodying improved locking means effectively preventing accidental unlocking and/or locking of the slider, and which slider is of simple construction, efficient in operation, and cheap to manufacture and assemble.

These and other objects and advantages of the invention will appear from the following description taken in conjunction with the accompanying drawing which forms a part thereof, and will be pointed out in the appended claims.

In the drawing:

Fig. 1 is a fragmentary view in perspective of a slide fastener embodying a slider constructed according to the principles of this invention;

Fig. 2 is an enlarged fragmentary longitudinal section taken substantially on the line 2—2 of Fig. 1, with the slider parts in locked position;

Fig. 3 is an enlarged fragmentary section taken substantially on the line 3—3 of Fig. 2;

Fig. 4 is a transverse section taken substantially on the line 4—4 of Fig. 2;

Fig. 5 is an exploded view, in perspective, of the slider locking member before assembly to the slider body; and

Fig. 6 is a view similar to Fig. 2 but showing the slider parts in unlocked position.

Referring to the drawing in detail, the illustrative fastener shown in Fig. 1 comprises a pair of stringer tapes 10, each reinforced at one edge and provided with a row of predeterminedly spaced interlocking fastener members 11 secured to the reinforced edge, in known manner. At the lower ends of the rows of interlocking fastener members, the stringer tapes 10 are secured together by a conventional bottom stop 12. Slidable on the rows of interlocking fastener members 11 progressively to engage and disengage them, to close and open the fastener, is a slider constructed according to the principles of this invention and generally designated 14.

The body of the slider 14 is formed by a front wing 15 and a rear wing 16 connected at their upper ends by a wedge or neck 17. Each of the wings 15 and 16 are provided with marginal side flanges 18 which form, with the wedge or neck 17, an upwardly diverging substantially Y-shaped channel 19 for guiding the interlocking fastener members 11 progressively into engagement to close the fastener and out of engagement to open the fastener, as is well known in the art.

The front wing 15 is provided with an aper-

ture 20 which extends completely through the front wing 15 into the channel 19. This aperture 20 receives and guides the locking projection in its tilting movement from unlocked position (Fig. 6) to locked position (Fig. 2), as hereinafter more fully described.

Extending forwardly, or outwardly, from the front wing 15 is a lug 21 which extends longitudinally from end to end of the front wing 15 and overlies the above described locking projection guiding aperture 20. The central portion of this lug is cut away to form substantially a loop, to provide an elongated space 22 between the lug and the underlying portion of the outer surface 15 of the front wing 15 adjacent the aperture 20. This space receives the loop or trunnion portions of the locking member which are confined in this space between the lug 21 and the front wing 15, as will hereinafter more clearly appear.

The locking member is generally designated 24 and, in the illustrated embodiment, comprises a relatively flat plate-like resilient member 25 and a second resilient member 26 secured thereto, as hereinafter more fully described.

The plate-like member 25 comprises a pair of similar leg portions 27 connected at their inner ends by a bar portion 28 from which extends downwardly, at substantially 90 degrees, a locking projection 29. The locking projection 29 is of substantially circular shape or, in other words, substantially complementary with the above described locking projection guiding aperture 20 which receives and guides the locking projection 29 in its tilting movement from unlocked position (Fig. 6) to locked position (Fig. 2), as stated above. It will thus be seen that the plate-like member 25 is substantially in the form of a loop with the locking projection 29 extending at substantially a right angle from the bar portion 28 at the loop end, or free end portion thereof.

The above described member 26 comprises a substantially rectangular handle-forming plate portion 30 having tabs 31 at each side, which tabs are adapted to be clamped about the ends of the leg portions 27 of the member 25, as shown in Figs. 1, 2 and 4, to secure the outer ends of the members 25 and 26 firmly together to make up the locking member 24. Extending from the plate portion 30 at an acute angle are a pair of similar parallel leg portions 32 which at their inner ends are bent inwardly at 33, at substantially 90 degrees and which terminate in trunnion projections or trunnion forming members 34. These members 34 extend oppositely and toward one another into close proximity in order to form

a trunnion. It will thus be seen that the above described member 26, like the member 25, is also substantially in the form of a loop, the loop portion being substantially closed and forming a trunnion.

In assembling the locking member 24 to the slider body, the leg portions 27 of the member 25 are caused to straddle the lower end portion of the lug 21 and the member 25 is thrust downwardly substantially to the position shown in Figs. 1 and 2. Thereafter, the leg portions 32 of the member 26 are bent away from one another to a position causing sufficient gap between the trunnion portions 34 to allow the passage of the lug 21 therebetween. The legs are then released and will snap to their original position wherein the trunnion portions 34 are in close proximity, as shown in Fig. 5. The outer ends of the leg portions 27 are then substantially aligned with the outer end of the plate portion 30 and the tabs 31 are bent around the outer extremities of the leg portions 27, as shown in Figs. 1, 2 and 6, securely to attach the members 25 and 26 together.

When the members 25 and 26 are thus attached, the plane of the leg portions 32 is disposed at an acute angle to the plane of the leg portions 27. This angle is preferably such that a spreading effect is exerted between the free ends of the members 25 and 26 sufficient normally to spread them apart a greater distance than is permitted by their confinement in the space 22 between the lug 21 and the slider wing 15. In other words, there is always sufficient spreading force exerted between the trunnion portions of the member 25 and the locking projection 29 of the member 25 to cause firm engagement between the trunnion formed by the members 34 and the inner surface of the lug 21 and to cause the locking projection 29 to be thrust into engagement with interlocking fastener members 11 in the channel 19 when the member 25 is substantially parallel to the front wing 15, or in the flat or locking position of the locking member shown in Fig. 2. In that position it will be noted that the center of the loop or trunnion formed by the projections 34 is disposed downwardly of, or behind, the center of movement of the locking projection 29 or the free end of the bar portion 28. As shown in Fig. 6, when the locking member 24 is in unlocked position, the center of the trunnion formed by the projections 34 is disposed upwardly of, or forwardly of, that center.

It will thus clearly appear that movement of the locking member from locked to unlocked position, and vice versa, can be accomplished only by overbalancing the normal yielding spreading force exerted by the locking member, i. e., the free end portions, or loop portions, of the members 25 and 26 must be forced together against this resiliency, to move the locking member 24 beyond "dead center," from locked to unlocked position and from unlocked position to locked position.

This resistance to accidental movement of the locking member is, of course, enhanced by the friction between the loop portion or trunnion of the member 26 and the inner surface of the lug 21 since rocking movement of the locking projection 29 is accompanied by substantial sliding movement between the trunnion or loop portion of the member 26 and the lug 21. Thus, accidental unlocking of the locked slider is effectively prevented while the slider is maintained

unlocked until the locking member is brought past dead center, from unlocked to locked position, by force applied to the locking member.

While the illustrated slider has been shown applied to one conventional form of slide fastener, it is, of course, applicable to other known forms of slide fasteners. Likewise, while the slider body and lug are shown formed integrally, a construction particularly adapted to casting and/or molding from metallic or non-metallic materials, it is, of course, to be understood that the slider body and lug are susceptible of construction by other known methods wherein various parts are secured together in known manner to make up a unitary structure.

Likewise, the above described construction of the locking member 24 is merely illustrative since the locking member itself or its component parts may be formed in various ways from various materials. While both the members 25 and 26 are preferably resilient to a rather high degree, resiliency is necessary only in one of these members since a spreading force between the loop portions of these members may be readily achieved where only one of them is resilient. However, where both are resilient the resiliency in the locking projection 29 advantageously relieves the interlocking fastener members 11 from substantial and destructive strains during operation of the locking means.

It is, of course, to be understood that the above description is merely illustrative and in nowise limiting and that I desire to comprehend within my invention such modifications as are included within the scope of the appended claims.

Having thus fully described my invention, what I claim as new and desire to secure by Letters Patent is:

1. In a slider for slide fasteners including a body having a fastener member guide channel therein, with a lug at one side thereof and with an aperture at that side communicating with said channel, a locking member comprising a pair of superposed members disposed at an angle to one another and connected at one end only, a locking projection at the free end of one of said members guided in said aperture and tiltable into engagement with fastener members in said channel to lock said slider, and a transverse trunnion at the free end of the other of said members disposed between said lug and the slider body and slidably and rotatably engaging said lug, the free ends of said longitudinal members being constantly yieldingly spread apart.

2. In a slider for slide fasteners, a slider body having a fastener member guide channel therein, an aperture communicating with said channel and a lug on said slider body with a portion thereof spaced from said slider body adjacent said aperture, and a locking member comprising a pair of members connected at one end, at least one of said members being yieldable whereby the free ends are constantly spread apart, a locking projection at the free end of one of said members insertible through said aperture into said channel to lock said slider, and a trunnion at the free end of the other of said members disposed between said lug and the slider body and slidably and rotatably engaging said lug.

3. In a slider for slide fasteners, a body having a fastener member guide channel therein, having an aperture communicating with said channel and a longitudinal lug at the side adjacent said aperture with a portion thereof spaced from said slider body, and a locking member

comprising a pair of members connected at one end only and having their other ends yieldingly spread apart, a locking projection at the free end of one of said members tilttable in said aperture into and out of engagement with fastener members in said channel to lock and unlock said slider, and a trunnion at the free end of the other of said members disposed above said locking member and also between said lug and the slider body and slidably and rotatably engaging said lug.

4. In a slider for slide fasteners, a slider body having a fastener member guide channel therein, an aperture communicating with said channel, and a longitudinal lug having its central portion overlying said aperture and spaced outwardly therefrom, a locking member comprising a pair of yieldable members with a handle connecting them at one end only and disposed at an acute angle to one another, a locking projection at the free end of one of said members guided in said aperture and tilttable into engagement with fastener members in said channel to lock said slider, and a trunnion at the free end of the other of said members disposed between said lug and the slider body and slidably and rotatably engaging said lug, the angle between said yieldable members being sufficiently great to cause them to be stressed toward one another by confinement between said slider body and said lug, at least in the locking position of said locking member.

5. In a slider for slide fasteners, a slider body having a fastener member guide channel therein with an aperture extending from one side of said body into said channel, a loop like lug at one side of said slider body with a portion overlying said aperture and spaced from said slider body, and a locking member comprising a handle portion with a pair of loop members connected thereto at their outer ends only and extending therefrom at an acute angle to one another, at least one of said loop members being yieldable, the free ends of said loop members being disposed between said lug and said slider body and normally stressed by confinement therebetween, the free end portion of one of said loop members slidably engaging said lug and the other of said loop portions having a locking projection thereon rockable in said aperture into and out of said channel to lock and unlock said slider.

6. In a slider for slide fasteners including a

body with a fastener member guide channel therein, with an aperture communicating with said channel and with a longitudinal lug having a portion overlying said aperture and spaced outwardly therefrom, and a locking member comprising a pair of loop members connected at their outer ends only and with the loop portions at their inner ends confined between said lug and said slider body, a locking projection on the loop portion at the free end of one of said members guided in said aperture and tilttable into engagement with fastener members in said channel to lock said slider, and a trunnion on the loop portion at the free end of the other of said members frictionally engaging the inner surface of said lug and slidably and rotatably with respect thereto, the angle between said yieldable members being such as normally to spread their inner end portions apart a distance greater than the height of the space between said lug and said slider body, whereby said yieldable members are stressed by their confinement of their loop portions in said space.

7. In a slider, a body having a fastener member guide channel therein with a locking projection guiding aperture extending from one side of said body into said channel, a loop like lug on said slider body with a portion overlying said aperture and spaced outwardly therefrom, and a locking member comprising a pair of loop members connected at one end and extending at an acute angle to one another, at least one of said loop members being resilient, the loop portions at the free ends of said loop members being disposed between said lug and said slider body, one of said loop portions engaging said lug and the other of said loop portions having a locking projection thereon guided in said aperture and tilttable into and out of engagement with fastener members in said channel to lock and unlock said slider, the angle between said loop members being such as normally to spread said loop portions a distance greater than the space between said lug and said slider body, and the greatest stressing of said locking member by reason of confinement of the loop portions in said space occurring at an intermediate position of said locking member between locking and unlocked positions, defining a dead center past which the locking member must be forced between locking and unlocked positions of said locking member.

EMMETT C. HARTLEY.
